[57] CLAIM

The ornamental design for a tape measure case, as shown and described.

DESCRIPTION

FIG. 1 is a front, right side perspective view of a tape

1 Claim, 4 Drawing Sheets

measure case showing my new design;

FIG. 2 is a left elevational view thereof;

FIG. 3 is a right elevational view thereof;

FIG. 4 is a bottom plan view thereof;

FIG. 5 is a top plan view thereof;

FIG. 6 is a front elevational view thereof;

FIG. 7 is a rear elevational view thereof;

FIG. 8 is a right elevational view showing another embodiment of my new design for a tape measure case;

FIG. 9 is a left elevational view thereof;

FIG. 10 is a bottom plan view thereof; and,

FIG. 11 is a front elevational view thereof.

The front, right side perspective view, top plan view, and rear elevational view of the alternative embodiment of FIGS. 8-11 are omitted as being identical to FIGS. 1, 5, and 7 of the first tape measure case embodiment. FIGS. 2, 3, 8 and 9 are depicted in a reduced scale.

The broken line showings are for illustrative purposes only and forms no part of the claimed design.
